UNITED STATES PATENT OFFICE.

CHARLES NELSON, OF EAST NEW YORK, N. Y.

SLATE-FRAME.

SPECIFICATION forming part of Letters Patent No. 281,785, dated July 24, 1883.

Application filed March 29, 1883. (No model.)

To all whom it may concern:

Be it known that I, CHARLES NELSON, of East New York, county of Kings, and State of New York, have invented certain new and useful Improvements in Slate-Frames, of which the following is a specification.

This invention has reference to an improved slate-frame of that class in which a noise-muffling device is applied to the edge of the same; and the invention consists of a slate-frame provided with a noise-muffling edge-strip, which is covered by a suitable fabric and provided with spirally-wound cord, said strip being nailed or otherwise attached to the edge of the frame.

In the accompanying drawings, Figure 1 represents a front elevation of my improved slate-frame; Fig. 2, an end view of the same; and Fig. 3, a detail vertical transverse section on line *x x*, Fig. 1.

Similar letters of reference indicate corresponding parts.

A in the drawings represents a slate-frame, and B a noise-muffling strip that is nailed or otherwise fastened to the edge of the slate-frame A, which is for this purpose preferably rounded off at the corners. The strip B is made of one continuous piece of wood, pasteboard, or other suitable material, the width of the strip being equal, or nearly so, to the thickness of the slate-frame, and covered by flannel *b*, or other suitable fabric, that is retained securely on the strip by means of a spirally-

wound cord, *d*, which latter projects at both sides of the slate-frame when the strip is attached to the edge of the same, so as to form thereby a muffling device and protect the slate against breakage. The muffling-strip B is made of pieces of proper length, care being taken to fit the ends neatly together. The muffling-strip is made up in proper length independently of the slate-frame, and then attached thereto, whereby the slate can be manufactured at less expense for cord and labor, while presenting a very neat and finished appearance.

Having thus described my invention, I claim as new and desire to secure by Letters Patent—

1. The combination of a slate-frame and a wooden edge-strip attached to the edge of the slate-frame, said strip being covered by a suitable fabric retained by a spirally-wound muffling-cord, substantially as set forth.

2. A muffling-strip for slate-frames, consisting of an interior strip of wood, a covering of suitable fabric, and a retaining-cord wound spirally around the strip and fabric, substantially as specified.

In testimony that I claim the foregoing as my invention I have signed my name in presence of two subscribing witnesses.

CHARLES NELSON.
